Patented Apr. 23, 1918.

2 SHEETS—SHEET 2.

UNITED STATES PATENT OFFICE.

SAMUEL H. G. KILLMAN, OF PRINCESS ANNE, MARYLAND.

ENTRANCE-GATE FOR THEATERS, AMUSEMENT-PARKS, AND THE LIKE.

1,264,090.

Specification of Letters Patent. Patented Apr. 23, 1918.

Application filed November 18, 1916. Serial No. 132,152.

To all whom it may concern:

Be it known that I, SAMUEL H. G. KILLMAN, a citizen of the United States, residing at Princess Anne, in the county of Somerset 5 and State of Maryland, have invented certain new and useful Improvements in Entrance-Gates for Theaters, Amusement-Parks, and the like; and I do hereby declare the following to be a full, clear, and exact description of the invention, such as will enable others skilled in the art to which it appertains to make and use the same.

This invention relates to new and useful improvements in entrance gates for theaters, 15 amusement parks and the like, and the principal object of this invention is to provide a gate which is coin actuated so as to prevent persons from entering the theater or park without first depositing their admission fee in the device.

Another object of this invention is to provide a device having the reserve plates for receiving the coin interchangeable so that the price of admission may be varied.

25 A further object of the invention is to provide an entrance gate which is constructed to accommodate a large person and which is so arranged as to prevent two or more smaller persons from entering the gate at 30 the same time.

A still further object of the invention is to provide a novel coin actuated device by which the locking bolt of the gate is released.

35 With these and other objects in view, the invention consists in the novel combination and arrangement of parts which will be fully set forth in the following specification and accompanying drawings, in which:

40 Figure 1 is a front elevation view of a gate constructed in accordance with this invention,

Fig. 2 is a fragmentary top plan view of Fig. 1,

45 Fig. 3 is an enlarged horizontal sectional view of the lock and a fragment of a gate,

Fig. 4 is an enlarged vertical view through the lock showing a releasing plunger,

Fig. 5 is a longitudinal sectional view on

an enlarged scale through the lock showing 50 a spring for holding the locking bolt in inoperative position while the gate is being opened, and

Fig. 6 is a transverse sectional view through Fig. 4.

55 Referring to the drawing, 1 designates as an entirety, a gate comprising a hub, 2 having extending radially therefrom a plurality of panels 3. This hub is provided with a central shaft 4 which is journaled at opposite 60 ends in the horizontal support 5. The lowermost support 5 carries a suitable annular series of ratchet teeth which are adapted to coöperate with a pawl carried by one of the panels 3 of the gate to prevent the gate from 65 revolving in a reverse direction. Each of the gate panels is provided in its vertical edge with a recess 6 which opens into an enlarged recess 7 provided with an inclined bottom 70 wall covered with a suitable bearing plate 8 against which the end of the locking bolt engages. The locking bolt above referred to is slideable through a tube 9 mounted in suitable standards or uprights 10 which form 75 a gate post or support for the fence, wall or other inclosure.

The locking bolt is designated by the numeral 11 and is provided with a beveled end for engagement against the inclined plate 8, while the opposite end of said bolt is formed 80 with a hook 12, the purpose of which will appear as the description proceeds.

The end of the hook 12 opposite that joining the bolt 11 is extended as at 13 and provided with a suitable pusher block 14 against 85 which the coin, which will be more fully hereinafter described, engages. This extended portion 13 is slideable through suitable slots in the guide walls of the locking structure, which will be more fully herein- 90 after described.

Attached to the hook 12 is spring 15, the opposite end of which is connected to a suitable eye 16, attached to the gate post and this spring normally tends to slide the bolt 95 into engagement with the gate panels in order to hold the gate against rotation. A suitable guard 17 is attached to the standard

10 above and below the spring 15 to protect the same against injury.

The lock structure is generally designated by the numeral 18 and comprises a body 19 having longitudinal grooves 20 and 21 arranged in parallel relation therein, the groove 20 will contain the lock bolt releasing mechanism while the groove 21 will receive the coin and therefore the grooves will be 10 respectively known as the bolt releasing and coin receiving grooves. Formed in the wall between the grooves 20 and 21 is a longitudinal slot 22 which receives the extreme inner end of the extension 13 while a similar 15 slot 23 is formed in the wall of the groove 21 adjacent the standard 10. The block 14 is positioned within the coin receiving groove 21 and a suitable slot 24 is formed in the bottom wall of this groove, which slot is adapted to conduct the coin to a suitable tube 25 on which it is conveyed into any suitable receptacle. A cover plate 26 is provided for the body 19 and is removably attached thereto so that the coin slot 27 formed therein 20 may be varied to receive coins of various sizes in order that the entrance fee may be varied to meet various conditions.

Slidable in the coin groove 21 is the plunger head 28 formed with a plunger 29 which 30 projects through the front wall 30 of the slot and this plunger head carries an upstanding pin 31 and has connected thereto a contractile coil spring 32 which in turn is connected to the front wall and thus it will 35 be seen the plunger normally tends to move outwardly. As shown in Fig. 4 when the block 14 is at its forward position, the space between the block and the plunger head 28 is sufficient to receive a coin so that when 40 the plunger is pressed inwardly, the coin will engage the block 14, thus moving the same into the dotted line position as shown in Fig. 3 and bringing the coin directly over the outlet slot 24 simultaneously moving the 45 bolt to unlocked position against the tension of the spring 15. In order to momentarily lock the bolt in said position, a rocker arm 33 is provided which is pivotally mounted on a suitable pivot 34 and has 50 formed at its forward end an arm 35 for engagement with the upper inclined face 36 of the plunger head 28. The opposite end of the rocker arm 33 is provided with a down-turned finger 36' for engagement with 55 the lock for holding the bolt, which shall be more fully hereinafter described.

This lock for holding the bolt is designated by the numeral 37 and is bent to form a shoulder 38 which normally tends to move 60 upwardly in the path of the arm 13 so that when the bolt is moved into unlocked position, against the tension of the spring 15, the shoulder 38 will engage the arm 13 and hold the bolt against forward movement,

while the plunger 29 is pressed inwardly. 65 As soon, however, as the plunger is allowed to move forward under the influence of the spring 32, the inclined face 36 of the plunger head will engage the finger 35, thereby rocking the arm 33 on the pivot 34 70 and causing the finger 36' to engage the spring 37, to press the same downwardly as shown by the full line position in Fig. 5, thereby releasing the arm 13 and allowing the bolt to move to locking position under 75 the influence of the spring 15. In this way it will be seen that the operator of the device will have an opportunity to release the gate a length of time sufficient to allow him to 80 enter.

While in the foregoing there has been shown and described the preferred embodiment of this invention, it is to be understood that such changes may be made in the combination and arrangement of parts as 85 will fall within the spirit and scope of the invention as claimed.

Having thus described my invention, what I claim is:

1. A device of the class described including a sliding bolt, a hook at one end of the bolt and having an extending arm formed integrally therewith, a coin engaging block secured on said arm, a plunger, a head on the plunger adapted to engage the coin inserted between the block and plunger head to move the block rearwardly for moving the sliding bolt out of locking engagement, a spring adapted to engage the arm to hold the same inwardly, and allow the bolt to be 100 withdrawn while pressure is applied to the plunger, and means actuated by the plunger head to release the spring and the sliding bolt to permit it to be extended to locking 105 position.

2. A device of the class described including a sliding bolt, a hook on one end of the sliding bolt and having an extending arm, a coin engaging block formed on the arm, a plunger, a head on one end of the plunger and adapted to engage the coin for forcing the same into engagement with the coin engaging block to move the bolt into unlocked position, a spring adapted to engage the arm of the bolt for holding the bolt out of locking position while pressure is applied to the plunger, means actuated by the plunger head for releasing the spring, and a second spring secured to the hook for returning the bolt to locking position.

3. A device of the class described including a sliding bolt, a hook on one end of the bolt, an arm formed integrally with the hook and at right angles to the bolt, a coin engaging block secured to the arm, a plunger, a head formed on the plunger and having an inclined upper edge, said plunger head adapted to engage the coin for forcing the

same into engagement with the coin engaging block to slide the bolt into unlocked position, a spring adapted to be engaged by the arm for holding the bolt in unlocked position while pressure is applied to the plunger, a rocking lever having one end engaged by the inclined edge of the plunger head and its opposite end engaging the spring to release the arm to permit the bolt to slide to

locking engagement, and spring means to return the bolt to locking engagement.

In testimony whereof I affix my signature in presence of two witnesses.

SAMUEL H. G. KILLMAN.
